UNITED STATES PATENT OFFICE.

VIRGILIO A. R. FERNANDES, OF CAMBRIDGE, MASSACHUSETTS.

RADIO APPARATUS.

Application filed June 8, 1925. Serial No. 35,731.

This invention relates to radio apparatus and more particularly to a mechanism for tuning the instruments of the same.

The principal object of the invention resides in an apparatus for use in connection with radio receiving sets which permits the various instruments to be operated simultaneously at different rates of speed by the manipulation of one of the instruments, where-
10 by the set will be made more selective when tuning in signals of various wave lengths, thus assuring a clear reception in the tone of the signals.

Another object is to provide a single control for a multiplicity of tuning instruments used in radio receiving sets, but which permits each instrument to be independently operated with respect to the other instruments when desired.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a front elevation of a portion of the panel board of a radio receiving set.

Figure 2 is a top plan view of the same.

Figure 3 is a longitudinal sectional view on the line 3—3 of Figure 2.

Figure 4 is a transverse sectional view on the line 4—4 of Figure 3.

Figure 5 is a similar view on the line 5—5 of Figure 3.

Figure 6 is a similar view on the line 6—6 of Figure 3.

Figure 7 is a detail perspective view of one of the actuating levers.

Figures 8 and 9 are detail views showing the different positions of the cams.

Referring more particularly to the drawings, the reference numeral 10 designates the panel board of a radio receiving set which is usually constructed of insulating material such as bakelite, and which supports a plurality of radio instruments such as condensers A, B and C, each of which includes a set of stationary plates S and a set of rotatable plates R, mounted upon shafts 11, 12 and 13 respectively, which are in turn journalled in the panel board 10 and a bracket 10' which extends the length of the

panel board on the back thereof. Although I have specifically mentioned that the instruments are in the form of condensers, it will be readily understood that my invention might be used in connection with other instruments which include a shaft to be rotated. It is, of course, understood that the rotatable plates R of respective disks are adapted to be rotated, one with respect to the other in order to clearly tune in the radio signals. It is therefore my invention to provide a means for simultaneously operating the rotatable plates at varying degrees of rotation in order to expedite the tuning operation, and to assure a finer adjustment of the instruments. Broadly, my invention includes a means 14 for transmitting motion from the instrument A to the instrument B, and a similar means 15 for transmitting motion from the instrument B to the instrument C. Although I have shown only three instruments, it will be readily appreciated that any number of instruments may be operated in a similar manner.

Controlling means 17 and 18 are respectively provided for regulating the transmitting means 14 and 15. The transmitting means 14 and 15 being identical in construction it is believed that a description of one will suffice for the other. Each means comprises a lever 19 having an enlarged head 20 formed with a slot 21 therein. The shaft 11 passes through the slot 21 and has a wheel 22 keyed thereon which carries a pair of diametrically opposed pins 23 for co-acting engagement with the straight side wall 24 of the slot 21. The opposite side wall of the slot 21 is rounded or curved as at 25 for a purpose to be presently explained. When the lever is in an operative position, the same is moved twice in one direction on each revolution of the shaft 11 by reason of the pins 21 engaging the straight side wall 24 of the slot. The free end of the lever is provided with an angularly disposed finger 26 which overlies a gear 27 keyed to the next adjacent shaft 12 of the instrument B for co-action therewith. An elongated slot 27' is formed in the lever adjacent the free end thereof and through which an angularly disposed arm 28 and a pivoted lever 29 extends. An arm 30 extends from the lever 19 intermediate its ends, and has one end of a contractile spring 31 connected thereto, the

other end of the spring being stationarily secured to the panel or to the bracket 10'. This spring tends to pull the lever in a direction so that the straight wall 24 of the slot 21 will be positioned in the path of movement of the pins 23, but the lever is limited in its movement by the arm 28 abutting the end of the slot 27'.

The controlling means 17 and 18 above referred to are also identical in construction, so that a description of one will also suffice for the other. Each controlling means comprises a shaft 32 journaled in the panel board and the bracket 10' and which is provided with a manipulating knob 33 keyed to the outer end of the same. An indicating pointer may be inscribed on the knob for co-action with graduations of an indicating scale inscribed on the outside of the panel board for visually indicating the different positions of the cams about to be described. A cam 34 is keyed to the shaft 32 and contacts with the depending arm 30 for controlling and limiting the backward movement of the lever 19 against the tension of the spring 31, and when the highest point of the cam is moved into engagement with the arm, the lever will have been moved to a position where the pins 23 will not touch the flat end wall 24 as the shaft 11 is rotated. The spring 31 tends to retract the lever and by reason of the shape of the cam, it is possible to vary the degree of movement of the lever in one direction. A second cam or finger 35 is also mounted on the shaft 32 in the path of the tail of the pivoted lever 29, and when contacted by the cam, the lever raises the free end of the finger 26 of the lever 19 out of contact with the gear 27 to various horizontal planes. It will therefore be seen that by varying the horizontal planes of the finger 26, and controlling the limit of movement of the lever 19, the gear 27 may be moved at varying speeds with respect to the wheel 22, which in turn causes the shafts 11 and 12 of the respective instruments to likewise rotate.

The same construction exists in the transmitting means 15 and in the control means 18, but it will be seen that when the shaft 11 is continually rotated, the speed of the same will be greater than that of the shaft 12 as an intermittent movement is imparted thereto, and the shaft 12 will rotate at a greater speed than the shaft 13. The ratio between the shafts may vary, for instance, the shaft 12 may complete one revolution to twenty revolutions of the shaft 11, while the shaft 13 may turn one revolution to twenty revolutions of the shaft 12. This ratio is capable of being varied by the operation of the control means 17 and 18 as hereinbefore mentioned.

From the foregoing description, it will be seen that the respective instruments may be

operated simultaneously by the operation of the manipulating knob 36 keyed to the shaft 11, or the transmitting means 14 may be rendered inoperative by the manipulation of the control means 17 so that rotation of the manipulating knob of the shaft 12 will only cause the instruments B and C to be adjusted. If desired, each of the instruments may be independently operated by the operation of the means 17 and 18 which throws the respective levers 19 out of co-acting engagement with the respective gears. By providing a device of this nature in a radio receiving set, it is possible to more accurately tune in the signals, thereby producing a clearer reception.

To prevent retrograde movement of the wheels 27 upon the backward movements of the levers 19, I provide flat tension springs 37 which are secured to the panel or bracket and bear against the wheels. However, if the bearings supporting the instrument shafts are tight, such springs are not necessary.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:

1. In combination with a plurality of radio instruments each having a rotatable shaft, means for selectively transmitting an intermittent motion to certain of said shafts upon the continuous rotation of one of said shafts, each of said means including a wheel keyed to a respective shaft, a gear keyed to the next adjacent shaft, a lever operable by said wheel at predetermined intervals during each revolution of the same, said lever co-acting with said gear for moving the same in one direction, means for automatically returning said lever after each movement by said wheel, and means for controlling the extent of movement of said lever.

2. In a radio apparatus, the combination with a pair of rotatable shafts, a wheel keyed to one of said shafts, a gear keyed to the other of said shafts, a lever having a portion for co-action with said gear, co-acting means between said lever and said wheel for imparting an intermittent movement to said lever in one direction for engagement with said gear on each revolution of said first shaft, and means for automatically moving said lever in an opposite direction.

3. In a radio apparatus, the combination with a pair of rotatable shafts, a wheel keyed to one of said shafts, a gear keyed to the other of said shafts, a lever having a portion

for co-action with said gear, co-acting means between said lever and said wheel for imparting an intermittent movement to said lever in one direction for engagement with said gear on each revolution of said first shaft, means for automatically moving said lever in an opposite direction, and means for rendering said lever inoperative to permit said shafts to be manually operated one with respect to the other. ¹⁰
In testimony whereof I have affixed my signature.

VIRGILIO A. R. FERNANDES.
